Term of patent 14 years

(Cl. D70—1)

Fig. I

Fig. 2

FIG. 1 is a front perspective view of a sewing machine showing my new design, and

FIG. 2 is a rear perspective view thereof.

The essential features of my design reside in the portions shown in full lines and consists primarily in the raised portion on the front face of the machine extending from the swing-out cover plate which conceals the zigzag pattern cam and gradually merges into the standard adjacent to the hand wheel, all as shown.

I claim:

The ornamental design for a sewing machine, substantially as shown and described.
